JOHN E. COVEY, OF CHICAGO, ILLINOIS, ASSIGNOR TO SWIFT AND COMPANY, OF CHICAGO, ILLINOIS, A CORPORATION OF ILLINOIS

CLAMP BACON HANGER

Application filed October 5, 1931. Serial No. 562,956.

The invention relates to a clamp bacon hanger.

The object of the present invention is to provide a simple, practical and efficient clamp bacon hanger of the safety skewer type equipped with a suspension clamping lever arranged to engage the lean side of a belly or bacon slab and cooperating with the skewer to form a clamp for preventing distortion or curling of the bacon slab while smoking and curing the same.

A further object of the invention is to provide a clamp bacon hanger of this character in which the weight of the meat when attached to the hanger will operate to throw the clamping lever into position and will cause the clamping lever to automatically follow the meat as the same shrinks and to act as a support for the fat and lean meat which would otherwise sag down out of position during the process of smoking.

A further object of the invention is to provide a clamp bacon hanger having an adjustable supporting device for making contact with smoke house trolley frames adapted to enable either a right or left belly to be effectively hung in the hanger in an off center position whereby a square shape is secured as the contraction of the belly side in smoking is greater than that of the back side and by hanging the bacon slightly off center the said unequal contraction is counteracted and a square shape is obtained.

It is also an object of the invention to provide a clamp bacon hanger of a length to accommodate bellies or slabs of bacon of different widths and equipped with means for engaging either a right or left belly to prevent the same from sliding along the skewer when the belly or slab is suspended off center through the adjustment of the suspension device.

With these and other objects in view, the invention consists in the construction and novel combination and arrangement of parts hereinafter described, illustrated in the accompanying drawings, and set forth in the claims hereto appended, it being understood that various changes in the form, proportion and minor details of construction, within the

scope of the claims, may be resorted to without departing from the spirit of the invention or sacrificing any of the advantages thereof.

In the drawings:

Figure 1 is a perspective view of a clamp bacon hanger constructed in accordance with this invention.

Fig. 2 is an end elevation of the same showing the hanger applied to a slab of bacon.

Fig. 3 is a vertical sectional view of the clamp bacon hanger, the adjustable transverse jaw being in elevation.

Fig. 4 is a front elevation of the clamp bacon hanger.

Fig. 5 is a perspective view of the clamp bacon hanger shown applied to a slab of bacon.

Fig. 6 is a perspective view of a clamp comb hanger shown applied to a slab of bacon and illustrating another form of the invention.

Fig. 7 is a vertical sectional view of the same.

In the accompanying drawings in which is illustrated the preferred embodiment of the invention, the clamp bacon hanger comprises in its construction a skewer frame composed of a horizontal fulcrum rod 1, approximately inverted L-shaped sides 2 and 3 and a skewer 4. The skewer frame is constructed of heavy wire or other suitable material and is preferably formed from a single piece of such material, the wire being bent at right angles successively to form the horizontal fulcrum rod and the L-shaped sides 2 and 3 which have upper horizontal portions and depending vertical portions. The lower end of the side 2 is bent inwardly and upwardly to form an approximately U-shaped keeper 5 which is open at the top and adapted to receive the pointed end of the skewer 4.

The wire at the lower end of the other side 3 is coiled or bent to form a spring loop 6 and is extended therefrom across the hanger to form the said skewer 4. The spring loop operates to maintain the free pointed end of the skewer in engagement with the keeper and the weight of the slab 7 when engaged by the skewer will maintain the same in the keeper. The hanger is adapted to be applied to either skinned or unskinned bellies or slabs.

of bacon and as illustrated in Fig. 5 of the drawings, all of the skin of the slab 7 is removed with the exception of a narrow strip 8 which extends across the upper end of the 5 slab and which is provided at intervals with cuts 9 forming narrow ribbons 10 of skin beneath which the skewer is laced.

The skewer may be passed through the hard fat beneath the skin, but it is preferable 10 to lace the skewer through the ribbons 10 of skin as by this arrangement a maximum portion of the skewer is arranged exteriorly of the edible portion of the meat and only a minimum portion of the skewer comes in contact 15 with said edible portion of the bacon. The cuts 9 may be made by any suitable means and the skewer acts as a form or straightening rod to cooperate with a clamping lever for preventing distortion or curling of the meat 20 while smoking and curing the same.

The clamping lever comprises two approximately inverted L-shaped sides 11 provided at their angles with eyes 12 formed by coiling the heavy wire or other suitable material of 25 which the clamping lever is constructed. The eyes are arranged on the fulcrum rod 1 at the ends thereof adjacent the inverted L-shaped sides 2 and 3 of the skewer frame and the said L-shaped sides of the lever frame 30 form lever arms which are arranged horizontally and vertically. The horizontal portions of the sides 11 are connected by a suspension rod 13 formed integral with the sides of the lever frame and arranged in parallelism with the fulcrum rod and the skewer and 35 provided at opposite sides of its center with stops 14 consisting of projections or lugs which may be welded or otherwise fixed to the suspension rod and which are adapted to limit 40 the adjustment of a supporting device 15 along the suspension rod of the clamping lever.

The supporting device preferably consists of a hook constructed of stout wire 45 which is doubled to form two sides and the wire is twisted at the shank 16 of the hook and the terminal portions of the wire are coiled at opposite sides of the lower end of the shank 16 to form extended eyes 17 which are 50 arranged on the suspension rod 13 and provide a resilient bearing sleeve for the supporting hook. The supporting hook is adapted to be arranged either in the central or off center position and when arranged in an off center position the strain to which the hook is subjected will cause the resilient bearing sleeve or eyes to frictionally grip the suspension rod and thereby prevent accidental independent sliding movement of 55 the supporting hook and the hanger rod.

The depending vertical portions of the sides of the lever frame are connected by parallel rods 18, 19 and 20 located at the lower ends of the vertical portions or sides 60 and forming a meat clamping jaw and pro-

vided with small projections or spurs 21 for engaging the lean side of the slab of bacon, but the said projections 21 may, of course, be omitted if desired, from one or more of the rods 18, 19 and 20.

The depending vertical portions of the sides 11 of the lever frame are provided at their lower ends with forwardly extending transverse jaws 22 for engaging the slab of bacon at the sides thereof. The fixed 70 transverse jaws are preferably formed by bending the wire of the sides 11 at right angles to form the lower portions of the jaws 22 and then upwardly at an acute angle 75 to form the inclined portions of the said 80 jaws 22, the terminals of the wire being welded to the vertical portions of the sides 11 of the lever frame, but the transverse jaws may be of any other desired construction, as will be readily understood.

The clamping lever is also equipped with an adjustable transverse jaw 23 adapted to be arranged at either side of the center of the hanger to cooperate with either of the fixed transverse jaws 22 which are located 90 at the ends of the hanger and the adjustment of the intermediate transverse jaw enables slabs of bacon of different widths to be confined in the hanger against sliding movement along the skewer.

The intermediate adjustable jaw 23 is provided with a rigid screw 24 on which is mounted a vertical plate 25 having an opening 26 to receive the screw and provided with forwardly extending terminal flanges 27 100 which engage over the rod 18 and under the rod 20 for slidably mounting the intermediate transverse jaw on the said rods. The flanges 27 are provided with notches 28 to receive the inner end of the transverse jaw 23 and the said screw 24 is provided with a thumb nut 29 adapted to engage the plate 25 for throwing the same and the adjustable jaw 105 tightly into engagement with the parallel rods of the clamping lever. This will enable the adjustable jaw to be secured against sliding movement on the said rods for holding the said adjustable jaw in engagement with one of the side edges of a slab of bacon, as clearly illustrated in Fig. 5 of the drawings, the said slab being confined between the adjustable jaw 23 and one of the end jaws 22. This will prevent any sliding movement of the slab of bacon on the skewer when the hanger suspends the slab of bacon off center and by providing the fixed end jaws at the ends of the hanger the latter may be applied to right and left bellies and the bellies or slabs may be placed in the hanger at either end thereof accordingly as the right 115 or left belly is to be suspended in the hanger.

Also, the construction accommodates bellies or slabs of different widths. Also by confining the upper end of the slab of bacon between the transverse jaws the bacon is pre- 120 125 130

vented from spreading into fan shape and is maintained in a compact condition. The jaws or shoulders 22 on the sides or ends of the hanger are arranged at right angles to the cross rods 18, 19 and 20 and act as stops and hold the bacon whether a right or left belly and square one side of the hanging end. The sliding shoulder or jaw is adapted to compress the hanging end of the belly and hold the other side edge in a square position. With the sliding device it is possible to compress the thin belly side of the hanging end of the bacon and thus even the thickness of the entire end of the piece of meat. Also the flank pocket is somewhat thickened in this operation.

The cross rods 18, 19 and 20 are of similar diameter than the heavy wire of the clamping lever and the skewer frame and a relatively great area of lean or flesh side of the bacon is clamped thereby avoiding unnecessary penetration of metal bars into the flesh side of the bacon and increasing the surety of proper support and minimizing the size of contact marks on the bacon.

When the hanger is applied to the meat and subjected to the weight thereof, the weight of the slab of bacon will throw the clamping lever into proper clamping position and will maintain a positive clamping action on the meat as long as the same is suspended in the hanger and as the meat shrinks the clamp will automatically adjust itself to and follow the meat so that the upper end of the belly or slab will always be held in proper position.

The skewer which constitutes a straightening rod or form cooperates with the clamping jaw to prevent distortion or curling of the meat during curing or processing.

While the meat engaging jaw of the clamping lever is illustrated in the drawings as consisting of three parallel rods 18, 19 and 20, any number of the rods may, of course, be employed.

In the form of the invention illustrated in Figs. 6 and 7 of the drawings, the construction and operation of the device is the same with the exception of the means for engaging the skin side of the slab of bacon and instead of employing a skewer for this purpose, as illustrated in Figs. 1 to 5 inclusive, the frame 30 is provided with a horizontal fulcrum rod 31, approximately inverted L-shaped sides 32, and a skin engaging rod 33 connecting the lower ends of the approximately L-shaped sides 32 of the frame 30. The skin engaging rod 33 which is horizontal is provided at intervals with nail-like hooks 34 which pierce the skin 35 of the slab 36 of bacon. The nail-like hooks which are tapered and pointed are preferably curved slightly and are arranged at an inclination and extend upwardly and inwardly from the rod 33 when the sides of the frame

are arranged in the position illustrated in Fig. 7 of the drawings, in which the upper portion of the sides is approximately horizontal and the outer portion of the sides is substantially vertical. 70

While the nail-like hooks are adapted to be applied to a slab of bacon with the skin left entirely on the same, the slab 36 is shown in the drawings with the skin entirely removed except for a narrow strip across the upper end of the bacon and the upper edge of the narrow strip of skin is preferably separated from the slab to provide a skin flap 37 to be engaged by the said hook-nails. While the hook-like nails will readily pierce the skin 80 the latter may be drilled to provide holes for the same or cuts may be made in the skin at intervals to facilitate the engagement of the hook-like nails with the said skin. 85

The clamping lever 38 is constructed substantially the same as the clamping lever heretofore described with the exception that a greater number of rods 39 are provided for engaging the lean or flesh side of the slab of bacon. The construction and operation of the comb clamp bacon hanger illustrated in Figs. 6 and 7 of the drawings, are the same as the construction and operation of the form of the invention illustrated in Figs. 1 to 5 inclusive of the drawings with the exception of 95 the skin engaging means.

What is claimed is:

1. A clamp hanger of the class described, comprising a skewer frame having a skewer for engaging a slab of bacon at the skin side thereof, a clamping lever fulcrumed on the skewer frame and cooperating with the skewer to clamp a slab of bacon to the said skewer, and a supporting device provided with resilient eyes slidably mounted on the clamping lever and adapted to frictionally engage the same when the supporting device is moved to an off center position. 100

2. A clamp hanger of the class described, comprising a skewer frame having a skewer for engaging a slab of bacon at the skin side thereof, a clamping lever fulcrumed on the skewer frame and cooperating with the skewer to clamp a slab of bacon to the said skewer, said clamping lever being provided with a suspension rod, a supporting device provided with a terminal eye slidably mounted on the said suspension rod, and spaced stops carried by the suspension rod for limiting the movement of the supporting device. 110

3. A clamp hanger of the class described, comprising a skewer frame having a skewer for engaging a slab of bacon at the skin side thereof, a clamping lever fulcrumed on the skewer frame and cooperating with the skewer to clamp a slab of bacon to the said skewer, said clamping lever being provided with a suspension rod, and a supporting device having terminal portions coiled to form 125 a plurality of resilient eyes slidably mounted

on the suspension rod and adapted to frictionally engage the same when the supporting device is moved into an off center position.

4. A clamp hanger of the class described provided with means for engaging one side of a slab of bacon, clamping means for engaging the opposite side of the slab and relatively adjustable means carried by the clamping means and slidable thereon and arranged 10 to engage the slab at the edges thereof for compressing the bacon for preventing spreading of the same.

5. A clamp hanger of the class described provided with means for engaging a slab of bacon, fixed transverse jaws carried by the hanger at spaced points, and a relatively adjustable jaw mounted on the hanger between the fixed jaws and arranged to cooperate with either one of the same for engaging a slab of bacon at the side edges thereof.

6. A clamp hanger of the class described provided with means for engaging a slab of bacon, fixed transverse jaws carried by the hanger at the ends thereof, and an adjustable transverse jaw located between the fixed jaws and provided with a clamping member arranged to grip a portion of the hanger between the adjustable jaw and the said member for securing the said adjustable jaw in its adjustment.

7. A clamp hanger of the class described including a skewer frame having a skewer, a clamping lever fulcrumed on the skewer frame and provided with spaced rods forming a meat clamping jaw and arranged to cooperate with the skewer to clamp a slab of bacon and prevent distortion or curling, a fixed transverse jaw carried by the lever for engaging the slab of bacon at one side edge thereof, and an adjustable transverse jaw slidably mounted on the said rods for engaging the slab of bacon at the opposite side edge thereof.

8. A clamp hanger of the class described including a skewer frame having a skewer, a clamping lever fulcrumed on the skewer frame and provided with spaced rods forming a meat clamping jaw and arranged to cooperate with the skewer to clamp a slab of bacon and prevent distortion or curling, a fixed transverse jaw carried by the lever for engaging the slab of bacon at one side edge thereof, and an adjustable transverse jaw slidably mounted on the said rods for engaging the slab of bacon at the opposite side edge thereof, said adjustable transverse jaw being provided with clamping means comprising a threaded member, a plate mounted on the threaded member, and a nut also arranged on the threaded member and engaging the plate for clamping the rods between the plate and the adjustable jaw.

9. A clamp hanger of the class described including a skewer frame having a skewer, a clamping lever fulcrumed on the skewer

frame and provided with spaced rods forming a meat clamping jaw and arranged to cooperate with the skewer to clamp a slab of bacon and prevent distortion or curling, a fixed transverse jaw carried by the lever for 70 engaging the slab of bacon at one side edge thereof, an adjustable transverse jaw slidably mounted on the said rods for engaging the slab of bacon at the opposite side edge thereof, said adjustable transverse jaw being 75 provided with clamping means comprising a threaded member projecting from the adjustable jaw, the clamping plate arranged on the screw and having terminal flanges provided with notches receiving the adjustable jaw at 80 spaced points, and a nut mounted on the threaded member and engaging the plate for clamping the rods between the plate and the adjustable jaw to secure the latter in its adjustment.

10. A frame having means for engaging a slab of bacon at the skin side thereof, a clamping lever fulcrumed on the frame and cooperating with the same to clamp the slab of bacon, and a supporting device provided 90 with resilient eyes slidably and frictionally mounted on the clamping lever.
